(57) **CLAIM**

The ornamental design for a microscope, as shown and described.

DESCRIPTION

FIG. 1 is a front perspective view of a microscope showing my new design;

FIG. 2 is a front view of the microscope shown in FIG. 1;

FIG. 3 is a rear view of the pouring lid shown in FIG. 1;

FIG. 4 is a right side view of the microscope shown in FIG. 1 (with the left side view being a mirror image thereof);

FIG. 5 is a top view of the microscope shown in FIG. 1; and,
FIG. 6 is a rear perspective view of the microscope shown in FIG. 1.

The broken lines depicting various portions of the microscope show unclaimed subject matter.
